(57) **CLAIM**

The ornamental design for a coil component as shown and described.

DESCRIPTION

FIG. 1 is a front elevational view of a coil component, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a perspective view thereof;

FIG. 8 is a cross-sectional view taken along line VIII-VIII in FIG. 3; and,

FIG. 9 is a reference view with a cover removed.

The broken lines depict parts of the coil component that form no part of the claimed design. The dot-dash chain lines depict boundaries of the claimed subject matter and form no part of the claimed design.

1 Claim, 9 Drawing Sheets
